UNITED STATES PATENT OFFICE.

TOM JONES NODEN, OF LONDON, ENGLAND.

ROTARY SCRUBBER AND WASHER.

Application filed June 30, 1924, Serial No. 723,391, and in Great Britain July 16, 1923.

This invention refers to improvements in or relating to rotary scrubbers and washers for use in the manufacture of gas and the like, such for instance, as the purification of 5 gas and the absorption of ammonia, naphthalene, cyanogen, and benzol.

The invention has more particular reference to washer-scrubbers of the kind in which one or a series of revolving bundles, porous 10 screens, or elements are mounted to rotate within a cylinder or chamber containing the solvent liquid. Heretofore it has been the common practice in such apparatus to work with the liquid level almost up to the central 15 line or bearing shaft of the machine, or at any rate, sufficiently high to ensure the complete immersion of the lower sections or bundles, and it has also been proposed in such an arrangement to provide buckets on the 20 periphery of the bundles for the purpose of raising the water or liquid and causing it to percolate through the upper bundles, the said buckets being provided with perforated walls at their inner sides for this purpose.

25 The object of the present invention is to provide an improved rotary scrubber and washer having increased efficiency and capacity for a given size and which can be used with a less quantity of solvent than heretofore.

Now according to the present invention I provide a rotary scrubber and washer of the kind described for use in the manufacture of gas and the like having bundles or wetted 35 elements which are arranged to revolve entirely above or almost entirely above the level of the liquid so as to be more fully exposed to the flow of gas and a plurality of buckets associated therewith and so constructed and arranged as to dip into the liquid and pick up the solvent and to retain same during the lower portion of their upward travel and to discharge same over the bundles when at or near the top of their 40 travel.

In order that the present invention may be clearly understood and more readily carried into effect it is hereinafter described with reference to the accompanying drawings, in which:—

Figure 1 is a sectional side elevation of a single section of a five-bay rotary scrubber and washer constructed in accordance with the present invention;

55 Figure 2 is a diagrammatic end view il-

lustrating the arrangement of the buckets in relation to the solvent;

Figure 3 is a detail sectional view to an enlarged scale illustrating the arrangement of a bucket on the periphery of one of the bundles;

Figure 4 is a similar detail view illustrating one of the buckets detached from its bundle;

Figure 5 is an enlarged end or side elevation of said bucket;

Figure 6 is a plan view of said bucket, and

Figures 7, 8, 9 and 10 are substantially similar detail views to Figures 3, 4, 5 and 6 illustrating a bucket of greater width than the 70 width of the bundle to which it is secured, but having a mouth of the same width as the bundle.

As shown and in one convenient manner of carrying the present invention into effect the 75 improved machine may be built up in the well known manner in one or more outer cylindrical casings such as *a*, having a horizontally arranged shaft *b* driven by a suitable engine or gearing and carrying a plurality of radially arranged bundles *c* of corrugated iron, wood or other suitable or preferred material. The machine may be constructed in one or more sections or casings *a*

in the well known manner with one or more 80 intermediate bearings such as *d*, and may be provided with a connecting pipe *e* for the passage of the gas from section to section, and each section may comprise any preferred number of bays *a'* *a''* *a'''* *a''''* and *a'''''*, as will be 85

readily understood. The buckets *f*, which may, as shown, be of rectangular or other formation, as preferred, are suitably fixed, as by metal straps *g*, to the periphery of the circular plates *h* carrying the revolving bundles *c*, and conveniently one such bucket *f* would be provided in conjunction with each bundle *c*. The buckets *f* are so designed and angularly arranged that they do not begin to discharge their contents until at or near the horizontal centre line when the buckets are vertical, as indicated in Figure 2, and they discharge their total contents when at or near the top. For instance, the buckets *f* could be deep and narrow, as shown, with a relatively small or narrow opening or mouth *f'* at the inner leading edge. Thus in operation the plates *h* as they revolve carry with them the buckets *f* which are so shaped and 90

arranged that they pick up the solvent *i* in the 95

110

casings a at the lower portion of their travel, and then when at or near the horizontal centre line begin to distribute same evenly and regularly over the whole surface of the 5 said bundle c , after which the solvent i gravitates again to the bottom of the washer where it may be used again by the buckets f for a predetermined length of time, or partly returned to the adjoining compartment of 10 the washer. By this means it will be manifest that it is not necessary to provide a large quantity of solvent i and the level of the solvent in the washer can be considerably lowered as compared with the present practice, 15 being merely up to the underside of the circular plates h thus leaving exposed to the flow of gas the whole of the wetted area of the bundles, c . The level of the solvent i can be maintained constant by suitably arranging 20 the overflow pipes from one section to another.

The buckets f may, as in Figures 1 to 5, be of the same width as the bundles or they may, as in Figures 7 to 10, be of greater width than 25 the bundles. In the latter case the mouth is preferably made of the same width as the bundles, as will be readily understood. It will be obvious that the bundles c may if desired be increased in length towards the shaft 30 b , always providing that sufficient space is left for the passage of gas from one compartment to another; that is to say, a space equal in area to the area of the inlet and outlet gas connections.

35 The gas enters the machine at the left hand side of the same, flows inwardly through the bundle in a' , flows outwardly through the bundle in a^2 , then downwardly on the outside of said bundle in a^2 and between the same and

the wall of the casing in a^2 , flows outwardly 40 through the bundle in a^3 , then inwardly between the bundle and the wall of the casing in a^3 , then outwardly between the wall and the bundle in a^4 and inwardly through the bundle in said casing a^4 , outwardly through the bundle a^5 and then escapes through the outlet on the right hand side of the machine. 45

It will thus be seen that by the present invention it is possible to obtain an increase of 50 more than 80 per cent of the wetted area exposed to flow of the gas, as compared with present practice; to reduce considerably the amount of solvent carried in the washer and also the weight of the machine; to obtain improved wetting of the bundles with increased 55 absorption results; and also to obtain greatly increased capacity with a consequent proportionate saving in ground space and housing accommodation.

What I claim is:—

A rotary gas scrubber and washer, comprising a rotating series of bundles of elements to serve as the carriers of a solvent for the purification of a gas, and buckets associated with 60 said elements and constructed as hollow 65 bodies carried by the outer peripheral edges of the elements, said bodies having their major dimension circumferentially of the carrier and their minor dimension radially thereof, the leading end of the body being inclined 70 in a direction away from the elements and formed in such inclined portion with an opening 75 for the entrance and delivery of the solvent, said body being otherwise imperforate.

In testimony whereof I have hereunto signed my name.

TOM J. NODEN.
